[57] CLAIM

The ornamental design for a jug, substantially as shown and described.

DESCRIPTION

FIG. 1 is a front elevational view of a jug showing my new design, the opposite side being a mirror image of the side shown;

FIG. 2 is an elevational view taken from the left of FIG. 1;

FIG. 3 is an elevational view taken from the right of FIG. 1; and

FIG. 4 is a top plan view thereof.

Fig. 5
